STEREOTYPE PLATE CASTING MECHANISM

Nils Olsen Temte, Chicago, Ill., assignor to The
Goss Printing Press Company, Chicago, Ill., a
corporation of Illinois

Application October 21, 1936, Serial No. 106,721

7 Claims. (Cl. 22—2)

The invention relates to new and useful improvements in stereotype plate casting boxes and more particularly to such improvements in flat casting boxes employing vacuum suction on the matrices and casting plates of different sizes or column widths.

Objects and advantages of the invention will be set forth in part hereinafter and in part will be obvious herefrom, or may be learned by practice with the invention, the same being realized and attained by means of the instrumentalities and combinations pointed out in the appended claims.

The invention consists in the novel parts, constructions, arrangements, combinations and improvements herein shown and described.

The accompanying drawings, referred to herein and constituting a part hereof, illustrate one embodiment of the invention, and together with the description, serve to explain the principles of the invention.

Of the drawings:

Fig. 1 is a vertical central section through a flat casting machine embodying the invention; 25
Fig. 2 is an enlarged full horizontal section on line 2—2 of Fig. 1;

Fig. 3 is a side elevation looking at Fig. 2 from the top and showing the box in open position;

Fig. 4 is a plan looking down at the drag on 30 lines 4—4 of Fig. 3;

Fig. 5 is a fragmentary elevation on lines 5—5 of Fig. 1;

Fig. 6 is a fragmentary elevation on lines 6—6 of Fig. 1; and

Fig. 7 is a fragmentary end elevation of the 35 box-closing means.

The invention finds its present chief application in flat stereotype plate casting boxes and is directed mainly to producing a simple, sturdy 40 and economical mechanism utilizing vacuum suction and producing plates of different widths, usually from one column wide to any desired number of columns. With these and other objects in view the invention provides a casting chamber which may be varied in width by column units from one column up, and the vacuum suction is applied to the matrix or matrices of 45 any given width, and, if desired, a plurality of narrow side-by-side casting chambers may be employed, each having its own vacuum suction; and there is further preferably provided a vacuum held backing sheet in the drag, which likewise may be of various widths as desired, or may be acted on by vacuum for various parts of its 50 width. As embodied, a flat casting chamber is 55

provided comprising a drag movable between casting and delivery positions, and having a plurality of separate internal air suction or vacuum chambers, each preferably of column width, each chamber having its own air suction system with separate valve control for each air chamber. The drag has also means for holding one or more matrices of various unit widths, as required, the vacuum created in the aforesaid chambers acting on such matrices as are used in any particular casting, the vacuum being cut off from any part of the drag which may not be in use. The cope in this embodiment holds a back sheet to act as a non-conductor and to give a smooth back finish to the plates, and the cope is likewise provided with a plurality of unit width internal vacuum chambers, each having its own air conduits and valve control. Other features and objects of the invention will be set forth later herein, and it will be understood that the foregoing general description, and the following detail description are illustrative and exemplary, but are not restrictive of the invention.

Referring now in detail to the embodiment of the invention illustrated by way of example in 25 the accompanying drawings, the machine is shown having two vertically disposed side frames 1 and 2 connected together at their front ends by cross pieces 3 and 4, and at their rear ends by the casting box structure. The machine is 30 mobile, and the frame is mounted at its rear on a pair of rear rollers 5 and at its front on a pair of casters 6. The embodied mechanism is designed for the production of flat plates. The casting mechanism comprises an upright, fixed 35 cope 11 which is fixed to, and also serves to unite the side frames 1 and 2. The cope has laterally extending bosses 9 and 10 at either side, within the side frames, and bolts 12 and 13 pass through the side frames and are threaded into 40 the bosses 9 and 10. The cope has a flaring mouth 8 at the top for convenience in pouring. The cope is adapted to hold a backing sheet 45 within the casting chamber to provide partial heat insulation and to give the plates a smooth back finish. This back is acted upon by vacuum suction, and the vacuum is provided by a series of chambers extending vertically the length of the plate, and being of unit width, usually of column width, across the chamber, and these chambers communicate by a great number of small openings with the inner face of the cope. These means can create vacuum suction by unit sections across the casting chamber. As shown, the casting chamber is four columns wide and has 50 55

four vertically-disposed vacuum chambers 16, 17, 18 and 19 extending the length of the casting chamber and each approximately one column wide. These chambers communicate through a 5 large number of small openings 15 with the inner face of the cope to exert holding suction on the back sheet S. Each individual chamber is provided with means for creating and controlling vacuum in the individual chambers, and for this 10 purpose each of the chambers 16 to 19 has at its bottom end a laterally extending part 20, and a series of pipes 16^a, 17^a, 18^a and 19^a are provided each opening into the corresponding chamber, and each having a valve 25 by which the air 15 suction may be turned on or cut off. These four pipes communicate with a header 26 which is connected to the pump. A backing sheet S is mounted against the face of the cope 11 to constitute a non-conductor between the hot metal 20 and the cope and also to give a smooth finish to the back of the plate. There is preferably provided a chamber or chambers 28 back of the series of vacuum chambers, through which cooling water may be circulated, or within which 25 heating elements may be placed.

The drag 33 is movable between a vertical casting position and a horizontal position for inserting and removing mats and for removing the cast plates. In the embodied form of drag 30 moving and guiding means, there are fixed to the back of the drag and extending rearwardly therefrom at either side a pair of arms 34 and 35, and a shaft 37 is mounted in the outer end of said arms and extends across the machine. 35 The shaft 37 is also pivotally carried in the upper end of a pair of arms 38 and 39, which arms are pivotally mounted at 40 and 41 upon the two side frames, respectively. Also as a part of the drag moving and guiding mechanism, two rollers 43 and 44 are mounted on short shafts 46 and 47 which shafts are fixed to and project from either side of the drag. These rollers support the drag at either side and run, respectively, on horizontally-disposed tracks 48 40 and 49 formed on the top edges of the two side frame members 1 and 2 of the machine. These tracks terminate in two upwardly projecting curved stops 50 and 51, which limit the rearward travel of rollers 43 and 44. A pivoted latch 52 45 engages the projecting end of shaft 46 and holds the drag in the open position.

Means are provided for holding in casting position on the drag mats of different unit widths and for dividing the casting chamber into similar units for casting plates of different widths. In the present instance, plates of either one, two, three or four columns wide may be cast. In the embodied means, a stop or header 61 55 extends across the face of the drag near its bottom end and constitutes the bottom of the casting chamber. The member 61 is supported in inclined recesses in two brackets 62 and 63 which are fixed to either side of the drag, the header when so supported resting against the inner face of the drag and as stated constituting the bottom of the casting chamber. One or more vertically-disposed strips or stops 65 60 are positioned against the inner face of the drag with their square bottom ends abutting against the side of the bottom stop 61, these vertical stops being positioned to cast one or more plates of a width or from one to four columns. These vertical stops are held in position by means of blocks or pieces 66 carried upon the vertical stops and abutting against the top end of the drag

and having a finger 67 overhanging the back of the drag. A clip 68 is pivoted at 69 on the block 66 and is spring-held in engagement with the back of the drag to hold the stops in position. These vertical stops are undercut as shown in Figs. 2 and 4 to receive and hold the vertical edges of the mats m. 5

The means for applying vacuum suction to the mat units, whether one or more columns in width, comprises internal chambers 15, 16, 17 and 18, 10 extending vertically substantially for column length within the drag, and each being approximately one column wide. A plurality of relatively small orifices 19 communicating between the chambers and the face of the drag provide 15 the means for exerting the vacuum suction upon the mats. To control the vacuum creating action, whereby each chamber may be cut in and out from the pump, depending upon the width of the plate or plates being cast, each chamber is provided with independent vacuum controlling means. For this purpose, each of the chambers 15 and 18, respectively, has a laterally extending upper part 34. Connecting with each upper part 34 of the respective chambers are 20 suction pipes 75^a, 76^a, 77^a and 78^a. Each of these pipes has a cock 85, and all of the pipes communicate with a header 86. The header 86 communicates by a flexible pipe 87 with the pump. A foot pedal 88 is shown for turning on 25 and off the suction from the pipe 87. The drag is preferably provided with a rear chamber or chambers 82 which may be used either to circulate a cooling medium or to provide a heating element, as may be found desirable or convenient. 30

Means for supporting and holding the drag and maintaining it in alignment are provided, and as embodied two pairs of recessed lugs 93 and 94 are integral with and extend outwardly 40 at either side of the top and bottom of the back face of the drag. Located in the recesses of each pair of lugs, respectively, are a pair of transversely disposed bars 97 and 98, which are rounded to fit into the lugs, but are otherwise 45 preferably square. A vertically-disposed, centrally-located brace member 102 is recessed at either end, the two recessed fitting, respectively, over the central portions of the two rods 97 and 98. The brace 102 is centrally apertured, and through this aperture projects a screw-threaded pin 103, which pin is fixed in and projects from a central core 104 in the drag casting. A nut 105 is screw-threaded on the pin 103 to hold the structure together. 50

The embodied means for clamping the cope and drag in casting position comprises two pairs of hooks 109 and 110, the upper hooks 109 being fixed on a shaft 111 extending transversely across the back of the cope, and being journaled in a pair of lugs 112 fixed to and projecting from either side of the cope. The lower pair of hooks 110 are fixed to a shaft 117 extending across the lower end of the back of the cope, the shaft being journaled in a pair of lugs 118 fixed to and extending outwardly from the cope. The hooks 109 and 110 hook over the squared ends of bars 97 and 98, respectively, to hold the casting chamber in closed position. The two pairs of hooks are connected to operate together, and for this purpose an arm 119 is fixed to the shaft 111 and an arm 120 is fixed to the shaft 117, and a connecting link 121 is pivoted at either end to the ends of the arms 119 and 120, respectively. A handle 123 is fixed to one end of the shaft 111 70

whereby the operator can actuate all the hooks to clamp the cope and drag together for casting, or to release the drag after casting. Means are provided for casting plates of different thicknesses, and as embodied, the squared ends of bars 97 and 98 which engage, respectively, with the hooks 109 and 110 are shaped to give different depths to the casting chamber. An end of bar 98 is shown with four hook-engaging surfaces either of which may be brought into position to coat with the hook 109 by turning the bar 98 by quarter turns. These hook-engaging faces are notched back from the flat surfaces of the bars and are so positioned as to give different depths to the casting chamber. Both ends of each bar 97 and 98 are so formed. The rails 65 forming the sides of the casting chamber and rail 61 forming the bottom thereof will be selected of proper thickness in each case.

20 The invention in its broader aspects is not limited to the specific mechanisms shown and described but departures may be made therefrom within the scope of the accompanying claims without departing from the principles of 25 the invention and without sacrificing its chief advantages.

What I claim is:

1. A stereotype plate casting machine including in combination walls enclosing a casting chamber, other walls cooperating with the exterior of one of the casting chamber walls to form a plurality of internal vacuum chambers of plate unit width, means for creating suction at will in one or more of said vacuum chambers, 30 means for holding matrices of various unit width against said casting chamber wall, means for holding a backing sheet against a wall of said chamber, including a plurality of vacuum chambers of plate unit width communicating by an 35 opening in said last-mentioned wall with the casting chamber, and means for varying the width of the casting chamber.

2. A stereotype plate casting machine including in combination walls enclosing a casting chamber, other walls cooperating with the exterior of 45 one of the casting chamber walls to form a plurality of internal vacuum chambers of column unit width, communicating with said chamber by means of an opening in a wall of the chamber, means for positioning one or more matrices one 50 or more columns in width against said casting chamber wall, and means for creating vacuum in the vacuum chambers that are behind the matrix or matrices used in a particular casting.

3. A stereotype plate casting machine including in combination walls enclosing a casting chamber, other walls cooperating with the exterior of one of the casting chamber walls to form a plurality of internal vacuum chambers of column unit width, communicating with said chamber by means of an opening in a wall of the casting 60 chamber, an insertible and removable strip

adapted to hold a matrix and to constitute a casting chamber side wall, said strip being positionable at different column widths in the casting chamber, and selectively operable valve means for applying suction to each of said vacuum chambers that are behind the matrix or 5 matrices used in a particular casting.

4. A stereotype plate casting machine including in combination walls enclosing a casting chamber, other walls cooperating with the exterior of one of the casting chamber walls to form a plurality of internal vacuum chambers of column unit width, communicating with said chamber by means of an opening in a wall of the casting chamber, an insertible and removable 10 strip adapted to hold a matrix and to constitute a casting chamber side wall, said strip being positionable at different column widths in the casting chamber, selectively operable valve means for applying suction to each of said vacuum 15 chambers that are behind the matrix or matrices used in a particular casting, and a plurality of vacuum creating conduits communicating with each of said vacuum chambers.

5. A stereotype plate casting machine including in combination walls enclosing a casting chamber, other walls cooperating with the exterior of one of the casting chamber walls to form a plurality of internal vacuum chambers of column unit width, communicating with said chamber by means of an opening in a wall of the casting chamber, insertible and removable strips 30 adapted to be spaced within the casting chamber in selected column width positions, said strips being adapted to hold a matrix edge and constitute a chamber side wall, and means connected to each of said vacuum chambers to create vacuum in one chamber independently of another. 35

6. A stereotype plate casting machine including in combination walls enclosing a casting 40 chamber, means for positioning matrices of various widths within the chamber, means for selectively applying suction to various sized areas of a casting chamber wall to hold various sized 45 matrices, and means for varying the size of the casting chamber so that suction may be applied to only that area in use for casting and corresponding to the matrix area.

7. A stereotype plate casting machine including in combination walls enclosing a casting 50 chamber, means for positioning matrices of various widths within the chamber, means for selectively applying suction to various sized areas of a wall of the casting chamber, means for applying suction to various sized areas of the opposite wall of the casting chamber to hold a backing sheet, and means for varying the size of the casting chamber so that suction may be applied to only that area in use for casting and corresponding to the matrix area. 55

NELS OLSEN TEMTE.
